UNITED STATES PATENT OFFICE.

ELISHA A. HEWITT, OF GROTON, CONNECTICUT.

IMPROVEMENT IN ROTARY CHURNS.

Specification forming part of Letters Patent No. 141,348, dated July 29, 1873; application filed February 12, 1873.

To all whom it may concern:

Be it known that I, ELISHA A. HEWITT, of Groton, in the county of New London and State of Connecticut, have invented a new Improvement in Churns; and I do hereby declare the following, when taken in connection with the accompanying drawings and the letters of reference marked thereon, to be a full, clear, and exact description of the same, and which said drawings constitute a part of this specification, and represent, in—

Figure 1, an end view; Fig. 2, a top view open; Fig. 3, a transverse section on line *x x*; Fig. 4, a transverse section on line *y y*, looking toward the end; and in Fig. 5, a longitudinal section on line *z z*, showing the inner surface of one side.

This invention relates to an improvement in that class of churning which have beaters arranged upon a revolving-shaft; and it consists in combining with the horizontal revolving shaft and radial beaters or arms longitudinally-projecting ribs upon opposite sides of the shaft, and diagonal ribs upon opposite sides of the churn, all as more fully hereinafter described.

A is the body or box of the churn, in substantially the usual form, made semicircular upon the bottom, and provided with a shaft, *B*, through the center, from which radiate the several beaters *C*. Upon the end of the churn the driving-wheel *D* is arranged, constructed with internal teeth working in a pinion, *E*, upon the shaft *B*, in order to multiply the revolutions of the shaft in substantially the usual manner. On this end of the churn a cylinder, *F*, is arranged, within which a valve-piston is attached to a rod, *G*, and this rod is worked by an eccentric, *H*, on the driving-shaft, as denoted in broken lines, Fig. 1. From the cylinder *F* a tube, *L*, leads to the inside and turns down, as seen in Figs. 2 and 4, so that as the shaft revolves the piston is worked, each revolution collecting and forcing air into the churn for the purpose of facilitating the process of

churning. On opposite sides of the churn are arranged two ribs, *N N*, on one side, and *M M* on the other side, as seen in Fig. 3 and in broken lines, Fig. 5, the ribs *N* running from the center near the top down toward each end, those on the opposite side running from each end near the top down toward the center, as seen in Fig. 5.

As the beaters revolve the cream is thrown against each side, striking the upper surface of the ribs *N* and, by the inclination of the ribs, is turned toward each end, thus carrying the cream from the center toward the ends on one side, and as the mass on the opposite side is thrown up against the ribs *M* it is turned by them and thrown toward the center.

In this class of churning it is well known that a difficulty occurs in consequence of the thickening cream or partially-formed butter adhering to the shaft and revolving with it, the centrifugal force at the shaft not being sufficient to throw the cream from the shaft. To overcome this difficulty I form upon opposite sides of the shaft a rib, *P*, curved upon the advancing side and flat, or nearly so, upon the opposite side, as seen in Fig. 3, giving to the shaft in transverse section a cam-shape or irregular form, the result of which is that the cream striking the shaft works rapidly out to the edge of these ribs and is there thrown out.

I claim as my invention—

The combination of the arms *C* radiating from the shaft, the projecting ribs *P* upon opposite sides of the said shaft and in the relative position to the arms described, with diagonal ribs or abutments *M N* upon opposite sides of the churn, the angles of the said ribs *M* upon one side being the reverse of the angles of the ribs on the opposite side, all substantially as described.

ELISHA A. HEWITT.
